(57) **CLAIM**

The ornamental design for a handheld cosmetics applicator, as shown and described.

DESCRIPTION

FIG. 1 is a top perspective view of a handheld cosmetics applicator in accordance with my design;

FIG. 2 is a bottom perspective view thereof;

FIG. 3 is a right side elevation view thereof; the unshown left side elevation being a mirror image thereof;

FIG. 4 is a front elevation view thereof;

FIG. 5 is a top plan view thereof;

FIG. 6 is a bottom plan view thereof; and,

FIG. 7 is an exploded bottom perspective view thereof.
